IMPROVEMENT IN TRAVELLING BAGS.

E. A. G. ROULSTONE, OF ROXBURY, MASSACHUSETTS.

Letters Patent No. 60,256, dated December 4, 1866.

SPECIFICATION.

TO ALL WHOM IT MAY CONCERN:

Be it known that I, E. A. G. ROULSTONE, of Roxbury, in the county of Norfolk, and State of Massachusetts, have invented an Improvement in Travelling Bags; and I do hereby declare that the following, taken in connection with the drawings which accompany and form part of this specification, is a description of my invention sufficient to enable those skilled in the art to practise it.

The invention relates to the construction of travelling bags or portmanteaus, and particularly in the manner of applying the bag, leather, or body to its frame, and to a covering of said frame, the purpose of the invention being to simplify the manufacture while at the same time producing a very durable and finished bag. In carrying out my invention, I form each half or jaw of the frame of a plate or strip of metal bent around for the upper side and ends of the bag as usual, and turn in from this strip a flange, having a series of slots or holes formed all along its surface; and against the outer side of this flange I apply together the inner edge of the body leather, a welt piece, and one edge of a covering strip for the frame, the last-named piece being next to the flange. I then pass the frame-covering strip over the frame, turn it over the outer edge of the same, then carry it along the inner face of the frame and its flange, and thence around the flange edge and over the edges first placed against the flange, and this done the three parts of the frame-covering strip, the edge of the body and the welt, lying together on opposite sides of the flange, are stitched through the slots formed in the flange, thus securing the body and frame and frame-cover together by a single series or line of stitches.

This is the construction constituting my present invention, and the drawing represents, at A, a cross-section of a bag embodying the same, the detail B, shewing a view of a part of the frame flange, and C a cross-section of a portion of the frame, enlarged from the main view to show more clearly the arrangement and method of uniting the parts.

For the better understanding of the construction, the bag is shown as having no lining, and the single heavy black lines at A denoting the leather or material making up the body of the bag and the covering of the frame.

a denotes the body having a general construction in any suitable manner; b, the frames to which the body is fastened. Each frame, b, has a flange, c, turned in from it, as seen at A and C, and all along this flange are punched slots, d, as seen at B. Against the inner surface of this flange I first lay one edge of a strip of leather, or other material, e, placing against that a welt, f, and against that one edge of the body a; then I draw the strip e all around the outer and inner surfaces of the frame, as seen at C, carrying it down across the outer face and around the edge of the flange to and over the inner surface of the edge of the body a, before mentioned, as placed against the welt; then I stitch all these layers together and secure them to the frame b by a series of stitches, g, passing through the slots d. The welt f may be formed of a single thickness, but preferably of a strip doubled and corded at the fold, as seen in the drawings, the cord forming a bead between the frame and the body, imparting a finished appearance to the bag. This welt, however, may be dispensed with, the other parts having the same relative arrangement, as shown. In forming the frame I consider it preferable to turn the edge of the flange a little, as seen at i, as the parts may be more tightly strained together by the stitches, and the recess made by such bend forms a groove in one frame for the edge of the opposite one to shut into when the bag is closed. It will readily be seen that, though this construction is exceedingly neat and durable, there is no particular amount of extra material used, no extra work is required, and the manipulation of the parts to bring them into position is very simple.

I claim the arrangement and manner of connecting together the body, the frame, and the frame-cover, substantially as shown and described. I also claim combining with the frame and its covering and the body the welt f, secured to the frame-covering and body, substantially as set forth.

E. A. G. ROULSTONE.
